UNITED STATES PATENT OFFICE.

JOHN H. MARTINDALE, OF CLEVELAND, OHIO.

COMBINED AIR AND GAS MIXER AND CONTROLLER.

No. 918,879.

Specification of Letters Patent.

Patented April 20, 1909.

Application filed December 16, 1907. Serial No. 406,596.

To all whom it may concern:

Be it known that I, JOHN H. MARTINDALE, a citizen of the United States, residing at Cleveland, in the county of Cuyahoga and 5 State of Ohio, have invented certain new and useful Improvements in a Combined Air and Gas Mixer and Controller, and do declare that the following is a full, clear, and exact 10 description of the invention, which will enable others skilled in the art to which it app pertains to make and use the same.

My invention relates to a combined air and gas mixer and controller, and the invention consists in the construction and combination 15 of parts substantially as shown and described and particularly pointed out in the claims.

In the accompanying drawings, Figure 1 is a sectional elevation of my invention in a 20 form adapting it more particularly to steam boilers, and Fig. 2 is an elevation of a battery of mixers looking from the inside of the furnace and corresponding to a look from the right of Fig. 1. Fig. 3 is an enlarged 25 central longitudinal section of one of the several mixers and parts associated therewith. Fig. 4 is a perspective view of one of my improved gas controlling valves, and Fig. 5 is a cross section of a mixer and parts on 30 line corresponding substantially to 5-5; Fig. 3. Fig. 6 is a perspective view of a series of valve controlling disks and shaft on which they are mounted.

The invention is shown herein as especially 35 adapted to steam boilers, but this represents only one of the several adaptations or applications, thereof and which are comprised in its complete conception, such as kitchen ranges, heating furnaces, dwellings and the 40 like. Obviously also, the sizes of the parts will vary according to the uses thereof, and there may be incidental changes here and there to meet different adaptations of the invention, but the mixer remains essentially 45 the same in all cases and constitutes the essence of the invention, as will be apparent in the further description and claims. The 50 said mixer or mixers are clearly shown in Fig. 3, and there may be as many of these as a given place of use may require and according to the amount of heat to be developed. In the present instance I show three 55 several series of mixers arranged horizontally one over the other and five in each series. These series together constitute a so-called battery, and a battery may consist of one or

more series or a plurality of the mixers, say two or more, and as all the mixers shown herein are alike in construction and operation, a detailed description of one will answer for all. Thus, in Fig. 1, we have a longitudinal section of one of the lower mixers in the several series, and in Fig. 3 an enlarged longitudinal sectional elevation thereof clearly illustrating all the details. As shown in these views B 60 represents a front supporting and containing body provided with a chamber C common to all the mixers, and E is a gas supply pipe for said chamber. The said base or body B is supported in front of the furnace (not 65 shown) in any suitable way, and is provided at its inner side with as many openings as there are mixers and which openings are provided with separate detachable caps or plates D, fixed in place by screws or bolts 70 d. The said caps or plates have central internally threaded holes supporting valve nipples N, threaded therein, and said valves have inside finished seats adapted to receive tapered or cone shaped valves V. The said 75 nipples further have a space internally sufficiently large to afford the valves necessary operating room back and forth, and an externally fluted or corrugated ring 3 is pinned at 2 within the end of the threaded shell or 80 shank of each nipple and which ring serves 85 the three fold purpose of a bearing for valve stem 4, a backing for spring 5 for the valve on the stem thereof, and as a screen to arrest possible foreign particles that might otherwise pass in with the gas and obstruct the 90 valves. Hence, also, these parts severally are removable for repairs and cleansing, and each mixer constitutes a complete unit in the organization. The said caps or plates D are 95 provided each with an externally threaded boss 7, upon which the mixer tubes M are threaded, and said tubes are each provided with two or more series of inwardly and forwardly projected or inclined air supplying 100 or feeding pipe shaped nipples or stems 8 running preferably in rows from end to end at regular intervals apart, and the said nipples or stems communicate with openings through the wall of tube M and are of gradually decreased length from end to end of said tube beginning with the longest about or at the point of gas injecting nipple N, as shown. By extending the said tubular air 105 stems or projections 8 into the said tube toward the middle thereof, and especially about the nipple, I cause the mixing or com-

mingling of the air and gas to begin at once, because the gas produces a syphoning action on the air under these conditions, and this continues throughout the entire length of the 5 mixing tube. Obviously the area over which the jet or stream of gas issuing through nipple N expands or widens increases gradually toward the discharge end of the mixer tube, and the air supply pipes or tubes 8 are 10 gradually shortened to accommodate themselves to these changes.

The total practical effect of this construction and arrangement of parts is to obtain a much more perfect admixture of gas and 15 air in a given length of mixer tube than is possible in a plain tube with mere holes through its side but omitting the tubular or pipe shaped feeders 8, which in all cases deliver the air directly into the gas area and 20 where the gas is exerting a suction upon the air.

Now, in order that the relative proportions of gas and air may be maintained at a uniform ratio throughout all manipulations of 25 the gas valve, and whether large or small volumes of gas be used, I provide two separate tubular sleeves, G and H, about mixer tube M.. The inner sleeve G is provided with holes g corresponding to the air supply projections 30 8, and the outer tube H has holes h corresponding to holes g, and sleeve G is adapted to be rotated upon tube M to graduate or govern the passage of air into the mixer, while tube H is adapted to be set at one 35 point or another to definitely fix the inflow of air, whether more or less.

The matter of relative proportions of air and gas to obtain perfect combustion and to economize gas has been especially considered 40 in this organization of my mixer, and I believe that the constructions and adjustments herein provided are adapted to maintain such relations of the parts as will afford the highest attainable economy of gas for the 45 amount consumed. Hence the inner tube G is operatively connected with gas controlling valve V, and said tube is practically a valve tube or tubular valve because it does govern the supply of air to the mixer. This unitary 50 operation and control of valves V and G repeats itself with each series of mixers respectively, three all told in this case. I might of course connect all the series under one operation, so that corresponding valves or one or 55 more valves in each series would be reached at a time, or all at the same time and in like or varying degrees or proportions, but I prefer the present arrangement which gives me progressive or successive control of the several 60 valves in each series. To this end I employ a rotatable shaft S for each series of gas and air mixers, and said shafts are located in chambers C and have their bearings in body B, and each shaft carries a disk for each 65 mixer in that series. These disks J, J¹, J²,

J³, J⁴, are fixed to rotate with their shaft and have recesses in their edges or peripheries of varying length according to the order in which they are to set in opening the gas valves V. Thus, the first valve to be opened 70 by the present arrangement is the middle one in the series of five, having disk J with a recess 10. A single valve in a series is opened at a time to keep control of the gas used and the heat produced, and it may be any one in 75 the series, but I prefer to begin with the middle one, and recess 10 is accordingly short but sufficient to rest the head of the valve controlling bell-crank lever L therein in which position the valve is closed. Each valve is 80 provided with a bell-crank lever of this kind, the lower arm of which engages in or with the extremity of valve spindle 4. In this instance each lever is pivoted in its angle on a projection or arm 11 rigid with cap or plate 85 D. The next or second disk to come into action is J¹, provided with a recess 12 of such length as to allow a sufficient measure of rotation of shaft S to open the valve to the first mixer before the second one is opened by said 90 disk. The third disk J² with its recess 13 is the third to act, and is correspondingly longer than recess 12 for a like purpose, and so on as to the remaining disks J³ and J⁴ and the recesses 14 and 15 therein of still greater 95 length, actuation of a valve through its lever not taking place till the head 9 of the lever rides out of its recess onto the periphery of the disk. Thus the valves in a given series are opened successively and one series after 100 another until all may be turned on.

The respective shafts S are provided with hand cranks for rotating them, and each crank or shaft has a pointer 16 adapted to work with an index 17 provided with numbers or characters to indicate how much gas has been turned on and the valves that are opened. In this way an engineer can tell exactly the amount of gas he is using, and having learned what he can do with the index at 110 a certain figure or a certain amount of gas he can set the device again to the same figure and be certain of the same results. By these means he can also see which valves are open.

Now referring again to the two sleeves or tubes G and H, it may be repeated that inner sleeve G is rotarily adjustable and outer outer sleeve longitudinally adjustable, and these sleeves or tubes have separate actuation or control, the outer sleeve being essentially to fix the admission of air to greater or less volume, and the inner sleeve for governing or regulating the volume of air to be admitted up to the maximum that sleeve H permits to pass when it has been "set" in any desired working position. That is to say, the said outer sleeve may be so adjusted as to open its holes h more or less to the mixer, and according to amount of draft of stack, as the more suction of stack the greater 125 130

amount of air drawn in. Then, having this tube fixed for the right amount of air under present conditions the tube or sleeve G further governs the inflow of air through its 5 holes g, which are opened more or less as the mixers may require.

Outer sleeves H in a given series of mixers are controlled simultaneously and uniformly by toothed sectors 20 on rotatable crank-10 shaft 21 engaging racks or teeth 22 on said sleeves. Inner sleeves G are controlled from valve controlling shafts S, each of which carries a toothed sector 23 engaging a gear 24 on shaft 25. Said shaft 25 has mounted there-15 on a series of double channeled cams or cam wheels P, corresponding to the sleeves G in each series of mixers, and said wheels P have each a circumferentially inclined cross groove or path 26 running from one of the side chan-20 nels 27 to the other and which constitutes the real cam portion of said wheels and determines the degree or distance of rotation of sleeve G. Each sleeve has a headed stem 28 running in said channels and grooves which 25 serves to rotate the sleeve to open and closed positions respectively as it traverses said cam 26 in one direction or the other when the cam is rotated. Furthermore said cams 26 are staggered more or less to correspond with the 30 location and action of the several valve controlling disks on shaft S and their recesses 10, 12 and so on, the idea being to operate the valve sleeve G and open the same when the valve V corresponding thereto is opened, 35 thus admitting air and gas simultaneously to each mixer in its turn. But air is admitted only when a gas valve is opened so as not to be required to heat more than the gas requires and only as much as is necessary to obtain 40 perfect combustion, the plan being to utilize the maximum quantity of air with the minimum quantity of gas, thus promoting economy in gas and maintaining ideal conditions in combustion.

45 The channels in cam wheels P extend around said wheels so that the arm 28 on sleeve G can run therein and not affect the position of said sleeve except when a shift of the sleeve is to be made to either open or close the same.

What I claim is:—

1. In a gas fuel equipment for furnaces, a gas mixer consisting of a perforated inner tube having inwardly projecting air conducting nipples about its inside and air controlling sleeves about the outside thereof, in combination with a gas supply member open to one end of said mixer, a valve for said member, and means to open said valve.
- 60 2. In gas fuel equipment for furnaces, a plurality of mixer tubes in substantially the same plane and a valve for each tube, a sleeve about each tube adapted to govern the supply of air thereto, and means to open and close the valve and the sleeve of each tube

simultaneously comprising a rotatable shaft to open the valve and another shaft parallel thereto to operate the said sleeve, said shafts being operatively connected.

3. In a gas fuel equipment for furnaces, a series of gas mixer tubes and each mixer having air inlet openings through its side and a separate valve in the end thereof, means to open said valve comprising a rotatable shaft and a disk thereon, an air controlling sleeve about each mixer tube having openings between its ends and operatively connected with said valve, and means to control the flow of air through said sleeve.

4. A gas mixer tube having a succession of air inlets between its ends in rows and a tubular projection inside open to each of said air inlets, and an air controlling sleeve about said tube having openings corresponding to said air inlets, a gas controlling valve at the base of said mixer tube and a shaft and intervening mechanism operatively connecting said valve and said sleeve to operate the same together.

5. In a furnace and the like, a gas mixer tube having a plurality of series of air inlet projections running lengthwise thereof and integral with the wall of said mixer tube, in combination with a rotatable sleeve about said mixer tube having holes corresponding to said projections and adapted to open and close the same.

6. A gas mixer tube for furnaces and the like having a plurality of series of air inlet projections inside lengthwise thereof and integral therewith and gradually decreasing in length from the base of the mixer to the discharge end.

7. A gas mixer tube provided with a plurality of rows of air inlet projections on its inside integral therewith and inclined in the direction of the discharge of the tube, said projections being gradually shorter toward the discharge end of the tube.

8. A gas mixer tube having integral air inlet projections on its inside successively between the ends of the tube and inclined at corresponding angles toward the discharge and open directly through the wall of the tube, whereby each projection takes its own air supply from without the tube and the mixing begins at the ends of said projections.

9. A gas mixer tube having integral air inlet projections inclined from the wall of the tube inwardly and forwardly, sleeves about said tube having openings corresponding to said projections, and means for separately operating said sleeves to determine the volume of air admitted.

10. A tubular gas mixer having tubular and inclined air inlet projections of varying lengths between its ends and all pointing to the axial center thereof, a rotatable sleeve next about said mixer and a slideable sleeve about said rotatable sleeve, said sleeves pro-

vided with air inlet openings adapted to register with said air inlet projections, a valve to admit gas and means to operate said valve and the said rotatable sleeve at the same 5 time.

11. A gas mixer having inclined air inlet tubes of gradually decreasing length from the base to the discharge end of the mixer, a valve controlled nipple discharging centrally 10 into said mixer between the ends of said air inlet tubes, a plurality of air controlling sleeves about said mixer, means to slide one sleeve and means to rotate the other sleeve to govern the size of the air inlet.

12. A series of gas mixer tubes having each a plurality of series of air inlet projections extending from the wall of the tube, and a support for said mixer tubes provided with a chamber common to all said tubes, a 20 valve for each mixer tube and means in said chamber adapted to open one of said valves at a time comprising a rotatable shaft and disks thereon and levers operated thereby controlling said valves.

13. A series of gas mixers each having a succession of air inlets between its ends and sleeves about each of said mixers having openings corresponding to said inlets, in combination with a shaft and cam to rotate 30 one of said sleeves and open and close said inlets and means to move the other sleeve lengthwise.

14. A series of gas mixers and a gas valve for each, in combination with air controlling sleeves about said mixers, a shaft; a plurality of cams on said shaft, and means on each sleeve coöoperating with a corresponding cam to open and close said sleeve, and operating connections between said shaft and said gas 40 valves.

15. A series of gas mixers having air inlets between their ends, an inner rotatable air governing sleeve over each mixer and an outer slideable sleeve over said inner sleeve 45 having openings adapted to adjustably fix the maximum air openings to said mixer through said sleeve.

16. A gas mixing tube for furnaces and the like having opposite tubular projections on 50 its inside open through the wall of the tube to receive air and projecting at an inward and forward inclination, said projections arranged in a plurality of series and gradually shortened as they approach the discharge 55 end of the tube.

17. A gas mixing tube having air inlet openings through its side and a rotatable sleeve with corresponding openings about said mixer, a cam to operate said sleeve having two circular channels about the same and a radially inclined passage connecting said channels, and a projection on said sleeve

adapted to run in said channels and passage and thus open and close said sleeve openings.

18. A series of air mixer tubes arranged 65 side by side and having air inlet openings at intervals between their ends, an inner rotatable sleeve provided on each mixer tube provided with air inlet holes corresponding to the openings in said mixer tube and a slideable outer sleeve provided with openings adapted to register with those in said inner rotatable sleeve, and means to adjust said outer sleeves to fix the maximum air opening through the same, and means to operate said 75 inner sleeves successively to control the supply of air to said mixer tube.

19. A series of mixing tubes having inwardly and forwardly inclined tubular air inlet projections about their inner sides to 80 conduct air into said tubes, a rotatable sleeve about each tube to govern the volume of air thus admitted, a shaft and a double channeled cam wheel thereon for each tube having an inclined groove leading from one of 85 said channels to the other and a projection on each of said sleeves engaged in said channels and adapted to rotate said sleeve about the mixer as the cam wheel is rotated.

20. A series of mixing tubes having air 90 inlet openings between their ends in two or more series, and a sleeve about each of said tubes adapted to govern the flow of air into the tube, in combination with a shaft and cam wheels thereon to rotate said sleeves, each 95 cam wheel having parallel channels and a transversely inclined groove leading from one channel to the other, a stem on each of said sleeves engaged in a corresponding cam wheel, and the said cam wheels being arranged to cause the said sleeves to rotate 100 successively.

21. The combination of a series of air mixers and an inner and an outer sleeve about each mixer, the said sleeves and mixers having corresponding holes in series 105 through the same between their ends for the passage of air, a shaft and a cam wheel on said shaft for each of said mixers and a projection on each inner sleeve adapted to engage a corresponding cam wheel and to be rotated thereby, a rack on each outer sleeve, a shaft and a toothed sector on said shaft for each of said racks, whereby said outer sleeves can be adjusted lengthwise to enlarge or 110 reduce the air passages into the said mixers, the flow of air thus limited being further 115 determined by the inner sleeve.

In testimony whereof I sign this specification in the presence of two witnesses.

JOHN H. MARTINDALE.
